Primary Examiner — Sanjeev Paul(74) Attorney, Agent, or Firm — Rowan TELS LLCCLAIM

The ornamental design for an inflatable bath pillow for head and neck, as shown and described.

DESCRIPTION

FIG. 1 is a top view of an inflatable bath pillow for head and neck, showing my new design.

FIG. 2 is a bottom view thereof.

FIG. 3 is a front view thereof.

FIG. 4 is a rear view thereof.

FIG. 5 is a left lateral view thereof.

FIG. 6 is a right lateral view thereof.

FIG. 7 is a top view of the inflatable bath pillow for head and neck in an alternate configuration; and,

FIG. 8 is a bottom view of the inflatable bath pillow for head and neck in a deflated configuration.

The broken lines shown in the drawing figures are included for the purpose of illustrating portions of the inflatable bath pillow for head and neck that form no part of the claimed design.
